Patented Feb. 3, 1925.

UNITED STATES PATENT OFFICE.

MARTIN PEARSON, OF ROBBINSDALE, MINNESOTA.

NAILING MACHINE.

Application filed September 13, 1922. Serial No. 588,034.

To all whom it may concern:

Be it known that I, MARTIN PEARSON, a citizen of the United States, resident of Robbinsdale, county of Hennepin, State of Minnesota, have invented certain new and useful Improvements in Nailing Machines, of which the following is a specification.

The object of the invention is to provide an improved nailing machine.

10 A further object is to provide an improved nailing machine of the type adapted to feed nails singly and successively by gravity down an inclined chute into position to be conveniently struck with a hammer.

15 A further object is to provide an improved nailing machine of the class described of light weight yet of durable construction embodying features making it very practical and convenient for manipulation.

20 The invention consists generally in various constructions and combinations all as hereinafter described and particularly pointed out in the claims.

In the accompanying drawings forming 25 part of this specification—

Figure 1, is a view in side elevation, partly in section, of my improved nailing machine.

Figure 2, is a plan view of the same with 30 cover of nail reservoir removed.

Figure 3, is an enlarged detail view showing a nail forced into material with consequent depression of detent actuating jaws.

35 Figure 4 is a sectional view on the line 4—4 of Figure 5.

Figure 5 is a sectional view on the line 5—5 of Figure 3.

Figure 6 is a similar view but with the 40 detent actuating jaws in raised position.

Figure 7 is a detail sectional view of the lower extremity of the nail chute.

In the selected embodiment of the invention herein shown a portable frame 8 is provided with hand grips 9 and 10 and with two supporting legs 11 and 12. The leg 12 is pivotally mounted at 13 on the frame 8 and may be held in a plurality of adjusted positions by means of the screw 14 in the frame co-operable with the slot 15 in the leg 12. The purpose of the adjustment is to maintain the forward delivery end of the machine at different working elevations corresponding to the length of the shank 16 of the nails used.

55 A reservoir 17 is mounted upon the frame 8 at its upper end and has two convergent

slots 18 and 19 to form reservoir tracks leading to the slot or track 21 provided by the spaced downwardly inclined strips 22 and 22^a on the frame. The nails are placed 60 in the reservoir 17 and aided by the V-shaped projection 23 fall into the slots 18 and 19 and are subsequently fed by gravity down the track 21.

A pair of opposed levers 24 are pivotally 65 mounted on the pins 25 and are normally retained by the spring 26 so that their forward ends, forming the jaws 27 are upwardly held adjacent the lower end of the track 21 so that a nail may pass from the 70 track to the jaws and be held in the position shown in Figures 1 and 2 when a hammer may drive the nail into the article to be nailed and the machine thereafter rearwardly pulled to release the nail. 75

Detents are disposed in the path of the nails down the track 21 to effect single feeding of nails onto the jaws 27. As shown in Figures 4 and 5 a detent 28 is normally held so that its finger 29 projects across the track 80 21 to prevent passage of a nail. The detent 28 is pivotally mounted at 31 to the web 32 integral with the downwardly inclined strip 22 and is held in its projected position by means of the detent spring 33 coiled about 85 the pin 34 positioned on the outwardly projecting flange 35 of the strip 22.

A second detent 36 is with its finger 37 pivotally mounted at 38 on the web 39 integral with the downwardly inclined strip 90 22^a and is normally held in its retracted position by means of the detent spring 41 coiled about the pin 42 positioned on the outwardly projecting flange 43 of the strip 22^a. The positions of the detents as described are 95 those assumed when the jaws 27 are in the position shown in Figures 3 and 4, the finger 29 of the detent 28 holding the column of nails in the chute 21. Upon rearwardly pulling the machine the jaws 27 are forced 100 upwards by means of the coiled tension spring 26, as shown in Figure 6.

The cams 44 and 45 integral with the opposed levers 24 bear against the detents 28 and 36, the finger 37 of the detent 36 being 105 returned to its projected position immediately behind the position of the detent 28, i. e., a space substantially equal to the diameter of one nail shank. As the finger 37 of the detent 36 returns to projected (column-holding) position the finger 29 of the detent 28 is retracted and the released nail slides 110

to the position at the extremity of the jaws for subsequent nailing.

To enable the nail between the two detents to freely slide onto the jaws 27 from the track 21 I provide lugs 46 preferably made integral with the outwardly projecting flanges 35 and 43 of the inclined strips 22 and 22^a. These lugs as shown clearly in Figure 3 and Figure 7 are of sufficient height to prevent the head of the succeeding nail from bearing down on the nail to be released, the frictional bearing of which might prevent the free release of the nail. A guard 47 fastened to the flanges 35 and 43 by means of the strips 48 is provided to keep the nails in position to freely slide down the track 21.

I claim as my invention:

1. A nailing tool comprising a nail reservoir, a nailing track communicating therewith, a pair of opposed spring actuated levers adjacent said track, detents arranged in the path of the nails, and cams mounted on said levers for contacting with said detents.

2. In a nailing tool, a nail reservoir, a track leading therefrom, spring pressed levers in opposed relation having forward ends forming jaws adjacent said track, detents disposed in the path of the nails in said track and adapted to deliver them one at a time to said jaws, and cams mounted on said levers and engaging said detents.

3. A nailing tool, a nail reservoir, a track leading therefrom, spring-pressed levers in opposed relation, having forward ends forming jaws adjacent said track to receive the nails one at a time, detents disposed in

the path of the nails in said track upon opposite sides thereof, and normally preventing the feed of the nails, and means on said levers for engaging said detents and moving the jaw of one detent outwardly, and the jaw of the other detent inwardly to successively release the nails one at a time.

4. A nailing tool comprising a suitable frame, a nail reservoir mounted therein, an inclined nailing track communicating with said reservoir, detents arranged in the path of the nails for releasing them one at a time, a pair of levers mounted adjacent said track and having forward ends projecting beyond said frame to receive the nails from said track, and between which ends the nail is supported while being driven, and means for operating said detents successively to release the forward nail and separate it from the succeeding one.

5. A nailing tool comprising a suitable frame, a nail reservoir mounted therein, an inclined nailing track communicating with said reservoir, detents arranged in the path of the nails for releasing them one at a time, a pair of levers mounted adjacent said track and having forward ends projecting beyond said frame to receive the nails from said track, and between which ends the nail is supported while being driven, and means mounted on said levers for engaging said detents and operating them to release the forward nail and separate it from the succeeding one.

In witness whereof I have hereunto set my hand this 6th day of September, 1922.

MARTIN PEARSON.
